UNITED STATES PATENT OFFICE.

CHARLES V. ROTE, OF LANCASTER, PENNSYLVANIA, ASSIGNOR OF ONE-HALF TO E. W. BROWN, OF LANCASTER, PENNSYLVANIA.

BRAKE.

1,382,551.

Specification of Letters Patent. Patented June 21, 1921.

Application filed April 26, 1920. Serial No. 376,581.

To all whom it may concern:

Be it known that I, CHARLES V. ROTE, a citizen of the United States, residing at Lancaster, in the county of Lancaster and State 5 of Pennsylvania, have invented new and useful Improvements in Brakes, of which the following is a specification.

The present invention relates to improvements in brakes, particularly of the character employed for railway cars and of the type in which the shoe or braking surface is 10 removably connected with the head or body of the brake.

One of the objects of the invention is to 15 provide a brake in which the shoe and head may be separated, by a lateral sliding movement of the shoe so that it will not be necessary to disconnect the brake from its supporting means or move it to a relatively 20 great distance from the wheel on which it is intended to act to effect such separation.

Another object of the invention is to provide a brake of the character referred to in 25 which the shoe and brake head are directly connected by a key in such manner that even if the shoe is worn completely through there 30 is no danger of the separated portions thereof becoming accidentally detached and falling to the ground.

A further object of the invention is to 35 provide means by which the standard M. C. B. brake head may be readily equipped with means permitting the brake shoe to be applied by a lateral sliding movement. With 40 the regular or standard M. C. B. design of head and shoe the latter can only be separated from the head by a forward movement, or movement away from the head and toward the wheel with which the brake 45 acts and, therefore, it is necessary to effect a considerable separation of the wheel and brake before a shoe can be removed or replaced. By the present invention, however, an "adapter" is provided which can be 50 readily attached to a head of M. C. B. design and which will provide for the positioning or removal of a shoe by a simple lateral sliding movement.

The foregoing and other objects of the 55 invention are accomplished by the construction illustrated in the accompanying drawings, in which:

Figure 1 is a side elevation of a brake constructed in accordance with the invention;

Fig. 2 is a face view, with the shoe re- 55 moved;

Fig. 3 is an elevation of the opposite side of the brake from that shown in Fig. 1;

Fig. 4 is a rear elevation of the shoe;

Fig. 5 is a sectional view on the line 5—5 60 of Fig. 1;

Fig. 6 is an elevation of another embodiment of the invention;

Fig. 7 is a face view of the part shown in Fig. 6 with the shoe removed. 65

Referring to the drawings, and particularly to Figs. 1 to 5, inclusive, 1 designates the head or body of the improved brake which, as shown, is of the standard M. C. B. design. In this type or form of head the 70 forward surface thereof is provided with a plurality of forwardly extending lugs or projections. The intermediate projections 2, 3, extend transversely across the face of the head and are provided with suitable 75 openings 4, to receive a locking or securing key, hereinafter referred to. The end or terminal projections on the face of the head are each divided into two sections 5, 5^a, by a longitudinally extending slot or groove 6, 80 and the shoe commonly employed with such a head is provided with lugs adapted to fit within said grooves 6, as well as with a lug or lugs that extend transversely of the head in the spaces between the lugs or projections 85 2, 3, and the terminal lugs on the head. Therefore, in order to separate a shoe from its head, or to position a new shoe on a head, it is necessary to move the shoe forwardly 90 from the head to enable the end lugs thereon to clear the terminal lugs 5, 5^a. This necessitates moving the brake to a considerable distance from the wheel and adjustment of the brake supporting devices is necessary 95 which consumes considerable time.

In the embodiment of the invention illustrated in Figs. 1 to 5, inclusive, the brake head 1 is provided with an adapter which comprises a metal frame including side members 7, 8, end members 9, 10, and intermediate transverse cross pieces or sections 11, 12. Said sections of the adapter are all preferably formed integral and it will be seen that the members 7, 8, 11 and 12 thereof, fit about the intermediate lugs 2, 3, on the brake head, while the end members 9, 10, lie adjacent the terminal lugs 5, 5^a, of the head. Each of said cross members 9, 12, 11, 10 of

the adapter is provided in its rear face with a notch, or an aperture is formed therethrough, to receive the locking key by which the removable shoe is connected with the 5 brake head, as will be hereinafter more fully explained.

The side member 7, of the adapter projects forwardly from the plane of the forward face of the brake head and portions 14, 15, 10 thereof overlie said surface of the head and serve as abutments to limit lateral sliding movement of the brake shoe in one direction. The other side member 8, of the adapter is so shaped that the portions thereof between 15 the cross members 9, 12,—12, 11,—and 11, 10, are substantially flush with or slightly in rear of the plane of the forward surface of the head so that the adapter provides a plurality of sockets extending transversely of 20 the head and open at the outer side thereof into which the lugs on a brake shoe may be freely introduced by a lateral sliding movement of the shoe. The inner ends of the sockets adjacent the ends of the brake head 25 are closed or partially so by the aforesaid abutments 14, 15.

Owing to the position in which the brake head stands and the manner in which the adapter is interfitted therewith, there is little 30 possibility of said parts being accidentally displaced even if the shoe, hereinafter referred to, is removed. However, to insure that the adapter will not be accidentally disconnected from the brake head a 35 suitable tie rod may be passed through apertures formed in lugs 16, 17, and the intermediate web of the brake head, suitable securing means, such as cotter pins being provided to retain the rod in position.

40 The shoe 20, of the brake is provided on its rear face with a plurality of lugs 21, 22, 23, adapted to severally fit fairly closely within the sockets formed by the members of the adapter when applied to the brake head 45 and which are arranged between the lugs on the brake head. As shown in Fig. 4, these lugs do not extend continuously across the rear face of the shoe but each is composed of two sections connected by a member 24, 50 which provides a passage adapted to align with the grooves 6, at the ends of the brake head and the passages in the intermediate lugs on the head and through the transverse members of the adapter so that when the 55 shoe is in position on the head, a key 25, may be passed longitudinally therethrough to secure the several parts together. It will be seen that this key engages directly with the shoe the adapter and the brake head and the 60 several members on these parts with which the key engages are so closely related that even if the shoe is broken transversely, the sections thereof will not be permitted to fall or become detached from the head.

65 It will be seen that the adapter may be

readily applied to the ordinary standard M. C. B. brake head and that when in position a shoe of the character shown can be easily positioned on the head or withdrawn therefrom by a lateral sliding movement so 70 that it is unnecessary to withdraw the brake to any considerable distance from the car wheel to remove or replace a worn shoe. It is merely necessary to remove the key 25, after which the shoe can be drawn directly 75 from the head by a sidewise movement.

The side wall or member 8, of the adapter is preferably provided with a laterally deflected substantially horizontal portion 8a, opposite the central socket or portion, and 80 this is intended to serve as a fulcrum for a short lever or bar which may be introduced beneath the member 24 of the central lug on the shoe to overcome any wedging action that may interfere with the free lateral sliding movement of the shoe.

While one of the principal objects of the invention, as hereinbefore stated, is to provide means by which the standard M. C. B. design of brake head may be adapted to have 90 a shoe positioned thereon or removed therefrom by a lateral sliding movement only it will be evident that some of the objects of the present invention may be attained if the adapter is an integral part of the brake 95 head. Such a construction is illustrated in Figs. 6 and 7 in which the head 1a is provided on its forward face with lugs 30, 31, 32, 33. Between the lugs 30, 31, and 32, 33 are, respectively, formed abutments 35, 36, which 100 serve to limit lateral sliding movement of the lugs 21, 23, on the brake shoe 20. As shown, the terminal or end lugs 30, 33, are provided with longitudinal grooves 37, so that if desired, a shoe of the form commonly 105 employed with the standard M. C. B. design head may be used.

It will be seen that by the invention the shoe may be reversed in case it has become 110 unduly worn.

It is thought that the manner of using and the importance of the invention will be understood from the foregoing description taken in connection with the drawings.

While the drawings illustrate and the foregoing description refers particularly to embodiments of the invention which are, at present, considered the preferred forms, it is to be understood that there can be modification in various ways of the particular 120 form shown without departing from the invention.

Having thus described the invention, what is claimed is:

1. A brake comprising a head provided 125 with means for attachment to a beam and having on its forward face a plurality of spaced, forwardly extending, projections, abutments positioned between said projections adjacent one side of the head, a shoe 130

- provided with spaced projections on its rear face adapted to enter the spaces between the projections on the face of the head and to permit the shoe to be bodily moved laterally to and from engagement with the head, such lateral engaging movement being limited by said abutments, and a removable key extending through the projections on the head and shoe and normally preventing separation thereof. 10
2. A brake comprising a head adapted to be connected to a suitable beam and provided on its forward face with a plurality of spaced, forwardly extending, projections, each having an aperture therein, a shoe provided on its rear face with a plurality of apertured projections spaced longitudinally of the shoe to interengage with the projections on the head, whereby the shoe may be applied to or removed bodily from the head by a lateral sliding movement, means on the head for limiting such lateral movement of the shoe in one direction and causing the apertures on the projections thereon to align with the apertures in the projections on the head, and a removable key inserted in the apertures in said projections to connect the head and shoe. 20
3. A brake comprising a head adapted to be connected to a suitable beam and provided on its forward face with a plurality of apertured lugs and at one side, between two of said lugs, with a laterally projecting fulcrum surface, a shoe having on its rear face a plurality of apertured lugs spaced to correspond to the spaces between the lugs on the head, whereby the shoe may be moved into and from engagement with the head by a lateral sliding movement only, abutments on the head coöperating with some of the lugs on the shoe for limiting such sliding movement of the shoe in one direction and insuring alinement of the apertures in the lugs thereof with the apertures in the lugs on the head, and a key extending longitudinally through the apertures in the lugs in the head and shoe and connecting said parts. 40
4. The combination with a brake head having on its forward face a plurality of forwardly extending projections, of an adapter comprising a frame fitted to the head about certain of said projections and providing a plurality of sockets that are open at one side of the head and closed at the opposite side, a shoe having on its rear face a plurality of lugs adapted to be moved to and from a position within said sockets by a lateral sliding movement, and a common means engaging the projections on the head, the adapter and the lugs on the shoe. 50
5. The combination with a brake head having on its forward face a plurality of forwardly extending projections, the projections at the ends of the head being slotted or formed with a key way and the intermediate projections having apertures therethrough in alinement with said slots, an adapter comprising a frame including a plurality of apertured cross bars, extending through the spaces separating the projections on the head, and side members connecting the ends of said cross bars, only one of the side members extending beyond the plane of the forward face of the head, a shoe having on its rear face a plurality of apertured lugs adapted to be moved to and from a position where the apertures in its lugs will aline with the key ways and apertures of the head and the apertures in the cross bars of the adapter by a lateral sliding movement, and a key adapted to extend through said key ways and alined apertures to connect the several parts. 75
6. The combination with a brake head, of an adapter detachably connected to said head and provided on the face thereof with a plurality of sockets open at one side only of the head, a shoe having on its rear a plurality of lugs adapted to be positioned within or withdrawn from said sockets by a laterally sliding movement, and means connecting said shoe to the head. 80
7. The combination with a brake head, of an adapter detachably connected to said head and provided on the face thereof with a plurality of sockets open at one side only of the head, a shoe having on its rear a plurality of lugs adapted to be positioned within or withdrawn from said sockets by a laterally sliding movement, and a locking key extending longitudinally of the shoe and the face of the head and directly engaging the head, adapter and shoe. 90
8. The combination with a brake head including a plurality of lugs projecting forwardly from its face, the end lugs being slotted and the intermediate lugs provided with apertures in alinement with said slots, an adapter comprising a frame surrounding said intermediate lugs on the head and abutments positioned within the spaces between said intermediate and end lugs of the head adjacent one side of the head, a shoe having on its rear a plurality of lugs adapted to be inserted in or withdrawn from the sockets formed between the lugs in the head by a lateral sliding movement, which movement is limited in one direction by said abutments, and means for holding the shoe in position on the head. 105
9. A frame adapted to be applied to a brake head and comprising longitudinal side members and transverse connecting members, one of said side members extending continuously from end to end of the frame and having an intermediate portion flush with the outer surfaces of the transverse members and the other side member having portions depressed below the outer faces of 110
- 120
- 125
- 130

the transverse members, whereby when the frame is applied to a brake head there will be provided a plurality of sockets, one of which opens through the face and one side 5 only of the head, so that a shoe may be applied to or withdrawn from the brake head by a lateral sliding movement, which movement will be limited in one direction by the wall of one of said sockets formed by one 10 of the sides of said frame.

10. A frame adapted to be fitted about the intermediate lugs of a brake head and including side members only one of which is adapted to project as far as the face of the

head, between said intermediate lugs and 15 the end lugs of the head, whereby it is adapted to provide sockets to receive lugs on a shoe and permit said shoe to be applied to or withdrawn from the head by a lateral sliding movement, the portions of 20 said frame projecting beyond the surface of the head between the intermediate and end lugs of the head constituting abutments to limit lateral movement of the shoe in one direction.

25

In testimony whereof I have hereunto set my hand.

CHARLES V. ROTE.
